(57) **CLAIM**

The ornamental design for the false eyelashes, as shown and described.

DESCRIPTION

FIG. 1 is a front, right, top perspective view of the false eyelashes, showing my new design;

FIG. 2 is a rear, left, bottom perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of detail 9 in FIG. 1;

FIG. 10 is an enlarged view of detail 10 in FIG. 1;

FIG. 11 is an enlarged view of detail 11 in FIG. 2;

FIG. 12 is an enlarged view of detail 12 in FIG. 2;

FIG. 13 is an enlarged view of detail 13 in FIG. 3;

FIG. 14 is an enlarged view of detail 14 in FIG. 3;

FIG. 15 is an enlarged view of detail 15 in FIG. 3;

FIG. 16 is an enlarged view of detail 16 in FIG. 5;

FIG. 17 is an enlarged view of detail 17 in FIG. 7;

FIG. 18 is an enlarged view of detail 18 in FIG. 7;

FIG. 19 is an enlarged view of detail 19 in FIG. 8; and,

FIG. 20 is an enlarged view of detail 20 in FIG. 8.

The dashed broken lines in the figures illustrating the base of the false eyelashes depict portions of the false eyelashes that form no part of the claimed design. The dash-dot-dash broken lines depict the boundaries of the enlarged detail views and form no part of the claimed design.

1 Claim, 20 Drawing Sheets
